(57) **CLAIM**

I claim the ornamental design for a corkscrew bottle opener, as shown and described.

DESCRIPTION

FIG. 1 is a perspective view of the right side of a corkscrew bottle opener.

FIG. 2 is a front elevation view of the corkscrew bottle opener illustrated in FIG. 1.

FIG. 3 is a rear elevation view of the corkscrew bottle opener illustrated in FIG. 1.

FIG. 4 is a top view of the corkscrew bottle opener illustrated in FIG. 1.

FIG. 5 is a bottom view of the corkscrew bottle opener illustrated in FIG. 1.

FIG. 6 is an elevation view of the right side of the corkscrew bottle opener illustrated in FIG. 1; and,

FIG. 7 is an elevation view of the left side of the corkscrew bottle opener illustrated in FIG. 1.

The portions of the corkscrew bottle opener in broken lines are shown for illustrative purposes only and form no part of the claimed design.
